UNITED STATES PATENT OFFICE.

JESSE J. HEAP, OF NEW YORK, N. Y., ASSIGNOR TO UNION SPECIAL MACHINE COMPANY, OF CHICAGO, ILLINOIS, A CORPORATION OF ILLINOIS.

ROTARY TAKE-UP FOR SEWING MACHINES.

Application filed April 11, 1919. Serial No. 289,213.

To all whom it may concern:

Be it known that I, JESSE J. HEAP, a citizen of the United States, residing at New York city, in the county of New York, State 5 of New York, have invented certain new and useful Improvements in Rotary Take-Ups for Sewing Machines, of which the following is a description, reference being had to the accompanying drawing, and to the 10 figures of reference marked thereon.

The invention relates to new and useful improvements in rotary take-ups for sewing machines, and more particularly to a rotary take-up used in connection with a threaded 15 looper.

Prior to my invention rotary take-ups for a threaded looper, having eccentric portions and co-operating thread guiding and thread holding fingers, have been used, as shown, 20 for example, in the patent granted to Russell G. Woodward, November 27th, 1906, No. 836,849. In the patented structure, referred to, there are two spaced take-up cam discs between which the controlling fingers 25 extend. In a device of this character, when the looper thread breaks, it is liable to be wound on to the shaft between the take-up discs and it is very difficult to remove the thread when so wound into the machine.

An object of the present invention is to 30 provide a take-up mechanism of the character shown in the Woodward patent, with a take-up cam which is substantially of one solid portion, so that there can be no chance 35 of the thread, if broken, winding between the sections of the take-up cam.

A further object of the invention is to 40 provide a take-up mechanism of the above character, with take-up fingers disposed upon opposite sides of the cam and co-operating therewith in its thread controlling action.

A still further object of the invention is 45 to provide a take-up mechanism of the above character, wherein the take-up cam is formed of one single part, and used with a single check finger for retaining the thread.

These and other objects will in part be 50 obvious and will in part be hereinafter more fully disclosed.

In the drawings which show by way of illustration one embodiment of the invention—

Figure 1 is a view showing a portion of

a sewing machine having my improved take-up mechanism applied thereto; 55

Figure 2 is a plan view of the parts beneath the work support;

Figure 3 is a side view of my improved take-up cam; 60

Figure 4 is a sectional view on the line 4—4 of Figure 3;

Figure 5 is a sectional view centrally through the take-up cam in a plane at right angles to the axis of rotation of the cam; 65

Figure 6 is a view showing more or less diagrammatically the bed plate, the rotating cam and the associated controlling fingers with the parts in position so that the cam is just starting in its take-up action on 70 the looper thread;

Figure 7 is a similar view, but showing the take-up cam in position for holding the looper thread after the maximum amount 75 of slack has been taken up;

Figure 8 is a similar view, but showing the take-up cam in position where the looper thread is entirely released from any action thereon;

Figure 9 is a top plan view, the cam being shown in position at the last part of its take-up movement. 80

In carrying out my invention, I have provided a rotary take-up mechanism for a threaded looper, which is in operation of 85 the general character of that shown in the Woodward patent, above referred to. In my improved take-up mechanism, the controlling cam is formed of one solid piece, having a groove in its periphery, throughout a portion thereof, in which the check finger for retaining the looper thread operates. This take-up cam has a concentric portion for holding the thread and the nose or extreme end of the check finger extends 90 into the groove a sufficient distance so as to retain the thread on the concentric portion of the rotating cam. The groove, however, is very shallow and located wholly at the periphery of the cam. At the opposite sides of the cam are fingers which co-operate with the eccentric portions of the rotary cam in taking up the slack in the looper thread and in transferring or shifting the looper thread on to the concentric 100 portion of the rotating cam. The check finger is mounted so that it may be adjusted for varying the time at which the looper

thread is released and the thread holding fingers at the sides of the rotating cam are also adjustable.

The essential features of my invention 5 consists in the forming of the take-up cam in one single piece, so that there is no liability of the looper thread, if broken, winding in or about the parts of the take-up cam, and in providing a single check 10 finger which co-operates with the single solid controlling cam for retaining the thread thereon, and also in providing the thread holding fingers at each side of the cam with which the cam co-operates in taking up the 15 slack in the looper thread.

Referring more in detail to the drawings, I have shown my invention as applied to a sewing machine having a bed plate 1, carrying a work support 2. The machine is provided with an overhanging arm 3, in which a 20 needle bar 4 reciprocates, carrying, as herein shown, a single needle 5. The needle bar is reciprocated by a needle lever 6 which is connected to the needle bar by a link 7. Co- 25 operating with the needle 5, beneath the work support, is a threaded looper 7. This looper is mounted on a looper carrier 8, which is pivoted at 9 to a looper rocker support 10, and the looper carrier is oscillated 30 by a link 11. These parts are of the usual construction in a double locked chain stitch mechanism, and description thereof is not thought necessary. It may be noted, however, that in this type of machine the looper moves forward into the needle loop, and this, together with the feed of the fabric and the looper side travel, forms the thread triangle consisting of the looper thread, the 35 needle thread loop and the body of the looper, in which triangle the needle enters in forming the stitch.

The rotary take-up cam of my improvement is designed particularly for controlling the looper thread, so as to insure the proper 45 formation of the thread triangle for the needle to enter and also to control the looper thread so as to give proper slack thereto for the movements of the looper at the rear end of its stroke and during the drawing up of the needle thread loops by the needle, whereby flat stitches will be formed.

Located beneath the work support is a main shaft 12. Mounted on said shaft 12 is my improved rotating take-up cam 13. The 55 construction of the take-up cam is best shown in Figures 3 to 5, inclusive. It consists of a solid portion having an opening 14 therethrough, which receives the main shaft and said cam is fixed to the shaft by a set-screw passing through the opening 15 in the cam. Said take-up cam is formed with a concentric portion 16, which is provided with a peripheral groove 17 lying in a plane 60 passing between the side faces of the take-up cam. This groove extends from one end of

the concentric portion to the other end thereof. The cam in operation turns in the direction of the arrow in Figure 5. Following the concentric portion 16 in the direction of rotation is a concentric portion 17 which merges into an eccentric portion 18 and preceding the concentric portion 16 is an eccentric portion 19 which likewise merges into the concentric portion 16. It will be noted that the peripheral groove 17 is very shallow and is wholly at the periphery of the cam. Disposed at one side of the take-up cam is a thread take-up finger 20 and at the opposite side of this take-up cam is a thread take-up finger 21. These take-up fingers, as herein shown, are independent of each other and are supported by a bracket 22 secured to the supporting bed 1. Said fingers extend forwardly, and, as above noted, on the opposite sides of the rotating take-up cam 13. These take-up fingers are mounted in horizontal openings near the upper end of the bracket 22 and are secured in position by set screws 23 and 24, respectively. Said take-up fingers extend forwardly and downwardly and terminate at a point in front of the main shaft 12 and below the eccentric portion 19 when the parts are positioned as shown in Figure 6, so that the looper thread will be carried by the rotating cam against these take-up fingers which causes the thread to follow upwardly along the eccentric portion 19 of the rotating cam and to be stripped therefrom on to the concentric portion following.

The looper thread is indicated in the drawings at 7. It is led from the supply through thread nippers 25 which may be of the usual construction and then through a thread guiding finger 26 at one side of the take-up cam and a thread guiding finger 27 at the other side of the take-up cam. These guiding fingers 26 and 27 are of the usual construction. They are mounted on the supporting bracket 22 and extend forwardly in a substantially horizontal plane. The take-up cam rotating between said thread guiding fingers will engage the looper thread carrying the same around into contact with the thread take-up fingers and the action above described takes place.

Mounted in the upper end of the bracket 22 and between the take-up fingers 20 and 21 is a stud 27. This stud is capable of vertical adjustment in the bracket and may be held in adjusted position by a screw 28. Said stud is provided with a horizontal opening which receives the shank of a check finger 29. Said check finger may, therefore, be adjusted in an endwise direction in the stud and is held in adjusted positions by a screw 30. Said check finger may be adjusted vertically by raising the stud, and may be adjusted horizontally by loosening the screw 30. The check finger extends hori-

zontally and is provided with a forwardly downturned nose 31, which is so disposed, relative to the take-up cam, as to lie in the peripheral groove 17^a in the rotating take-up cam, and thus serve to retain the looper thread when it is stripped from the eccentric portion of the cam or stud on to the concentric portion 16. The position of the nose of the check finger is such that as soon as the concentric portion 16 of the cam passes the same and the concentric portion 17 comes underneath the nose, the thread will be released. The thread nippers 25 are also mounted on the bracket 22. The looper thread after leaving the thread guiding finger 27 is lead directly to the looper.

The operation of my device is as follows—assuming that the take-up cam is in the position shown in Figure 6. At this time the looper is at the forward end of its stroke. The rotation of the cam 13 will cause the eccentric take-up portion 19 to co-operate with the thread take-up fingers 20 and 21 and take up the slack in the looper thread due to the backward movement of the looper and thereby maintain the thread triangle, above referred to, well open for the entrance of the needle into the same. The looper thread is gradually taken up until the point X is reached on the eccentric portion of the cam and then the thread is snapped or stripped off on to the concentric portion 16 of the cam. This release of the looper thread from further take-up action occurs when the needle in its descent is well into the thread triangle and should not occur until this condition is met. By adjusting the thread take-up fingers horizontally, the point at which the release of the thread from the eccentric take-up surface of the cam on to the concentric surface 16 may be slightly varied. When the looper thread is released from the take-up surface 19 on to the concentric surface 16, it is held in check by the check finger 29, the lower end of which, as above noted, projects into the peripheral groove 17^a a sufficient distance to hold the looper thread. By adjusting the endwise position of this check finger and also the up and down position, so as to maintain its relation to the curved surface of the cam, the amount of slack given to the looper thread immediately following the thread being cast from the take-up cam 19, may be varied. In other words, the farther the nose of the check finger is moved forwardly or to the right, as viewed in Figure 7 of the drawings, the more slack will be given to the looper thread. The looper thread is held by this check finger until the looper is near the rear end of its stroke. When the concentric portion 17 passes underneath the nose of the check finger, the looper thread is released. However, this concentric portion 17 is of a length sufficient to prevent too much slack being

given to the looper thread until the looper has cast the needle loop therefrom in its backward movement. At this time the eccentric portion 18 contacts with the looper thread and permits said looper thread to be given the greatest possible amount of slack. This takes place when the needle is reaching the last portion of its down stroke and when the looper is reaching the last portion of its backward movement. The slack, as previously mentioned, permits the needle thread to draw the previous needle thread loop up toward the underside of the fabric without any restraining interference from the looper thread.

It will be readily noted that, if the looper thread breaks, there are no parts of the rotating take-up cam which can catch the broken end of the thread and wind the looper thread in and about the parts of said take-up, and at the same time the looper thread is checked or held by a single check finger and is perfectly controlled by the thread take-up fingers co-operating with said rotary take-up.

It will be noted that the thread take-up fingers 20 and 21 extend a sufficient distance in advance of the axis of the shaft 12, about which axis the take-up cam rotates, that, if the machine is turned backward, these take-up fingers will hold the thread sufficiently out of the path of the eccentric surface 18 so as to prevent said eccentric surface from catching the thread and winding the same around the shaft.

It is obvious that minor changes in the details of construction and arrangement of parts may be made without departing from the spirit of the invention, as set forth in the appended claims.

Having thus described my invention, what I claim as new and desire to secure by Letters Patent, is:

1. A rotary take-up for sewing machines including a rotating shaft, a single take-up cam carried thereby and having a concentric portion formed with a segmental groove lying at the periphery of said concentric portion, said take-up cam having a smaller concentric portion and eccentric portions, the bottom of said segmental groove being flush with the periphery of the smaller concentric portion and the eccentric portion adjacent the ends of said concentric portion having said segmental groove.

2. A rotary take-up for sewing machines including a rotating shaft, a single take-up cam carried thereby and having an eccentric take-up portion and a concentric retaining portion, said concentric retaining portion having a peripheral groove formed therein, a check finger having its free end extending into said peripheral groove and operating to retain the thread on said concentric portion of said cam, take-up fingers

disposed on opposite sides of the cam and having downwardly curved portions at their free ends adapted to co-operate with the take-up portion of the cam for stripping the thread from said take-up portion of the cam on said concentric portion of said rotating take-up cam.

3. A rotary take-up for sewing machines including a rotating shaft, a single take-up cam carried thereby and having an eccentric take-up portion and a concentric retaining portion, said concentric retaining portion having a peripheral groove formed therein, a check finger having its free end extending into said peripheral groove and operating to retain the thread on said concentric portion of said cam, take-up fingers disposed at opposite sides of the cam and having downwardly curved portions at their free ends adapted to co-operate with the take-up portion of the cam for stripping the thread from said take-up portion of the cam on said concentric portion of said rotating take-up cam, and means for horizontally adjusting said take-up fingers for varying the time when said thread is stripped from the take-up surface on to said concentric surface.

4. A rotary take-up for sewing machines including a rotating shaft, a single take-up cam carried thereby and having an eccentric take-up portion and a concentric retaining portion, said concentric retaining portion having a peripheral groove formed therein, a check finger having its free end extending into said peripheral groove and operating to retain the thread on said concentric portion of said cam, take-up fingers disposed at opposite sides of the cam and having downwardly curved portions at their free ends adapted to co-operate with the take-up portion of the cam for stripping the thread from said take-up portion of the cam on said concentric portion of said rotating take-up cam, means for horizontally adjusting said take-up fingers for varying the time when said thread is stripped from the take-up surface on to said concentric surface, and means for adjusting said take-up fingers vertically and horizontally for varying the relative position of the same to the concentric portion of the rotary take-up.

5. A rotary take-up for sewing machines including a rotating shaft, a single take-up cam carried thereby, said cam having an eccentric take-up portion and a concentric retaining portion, said concentric retaining portion being formed with a peripheral groove, spaced take-up fingers at opposite sides of the cam co-operating with said take-up portion of the cam, a check finger having its free end extending downwardly and into the said peripheral groove for re-

taining the thread on said concentric portion, said take-up cam having a concentric portion following the concentric portion formed with a peripheral groove and of less radius, whereby when said last named concentric portion passes the take-up finger the thread will be released.

6. A rotary take-up for sewing machines including a rotating shaft, a single take-up cam carried thereby, said cam having an eccentric take-up portion and a concentric retaining portion, said concentric retaining portion being formed with a peripheral groove, spaced take-up fingers at opposite sides of the cam co-operating with said take-up portion of the cam, a check finger having its free end extending downwardly and into the said peripheral groove for retaining the thread on said concentric portion, said take-up cam having a concentric portion following the concentric portion formed with a peripheral groove and of less radius, whereby when said last named concentric portion passes the check finger the thread will be released, and said take-up cam having an eccentric portion following said last named concentric portion and shaped so as to give up further slack to the thread.

7. A rotary take-up cam for intermittently acting upon the thread to take up and allow feed of the thread, said cam including a concentric surface provided with a circumferential groove, and a concentric surface adjacent thereto and in line with the first-named concentric surface, the circumference of said last-named concentric surface being in line with the bottom of the groove in the first-named concentric surface.

8. A rotary take-up cam for intermittently acting upon the thread to take up and allow feed of the thread, said cam including a concentric thread engaging surface having a circumferential groove formed therein, a single concentric portion at one end of said groove on to which said groove opens, and an eccentric surface at the other end of said groove on to which said groove opens.

9. A take-up mechanism for sewing machines comprising a rotating take-up cam having an eccentric thread engaging surface, thread guides for guiding a thread in the path of the eccentric thread engaging surface, take-up fingers co-operating with said rotating cam, said fingers being disposed so as to release the thread from said eccentric surface when the take-up cam is turned in the wrong direction.

In testimony whereof, I affix my signature in the presence of two witnesses.
